UNITED STATES PATENT OFFICE.

WAYNE S. EVANS, OF PHILADELPHIA, PENNSYLVANIA, ASSIGNOR TO S. W. EVANS & SON, OF PHILADELPHIA, PENNSYLVANIA, A FIRM COMPOSED OF SAMUEL W. EVANS, WAYNE S. EVANS, AND MORTON E. EVANS.

UMBRELLA RIB AND STRETCHER.

1,405,824.

Specification of Letters Patent. Patented Feb. 7, 1922.

Application filed May 13, 1920. Serial No. 380,960.

To all whom it may concern:

Be it known that I, WAYNE S. EVANS, a citizen of the United States, residing in the city and county of Philadelphia, State of Pennsylvania, have invented a new and useful Umbrella Rib and Stretcher, of which the following is a specification.

My invention consists of an improvement in umbrella construction embodying a 10 stretcher of channelled or U-shape, the channel being of reversed form at an end thereof whereby while one portion is adapted to be pivotally mounted in a channelled rib another portion is adapted to receive the adjacent portion of the rib and embrace the latter and so folding the rib and stretcher in compact form as to occupy together small space and also to prevent torsion and twisting of the rib and stretcher.

20 The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a side elevation of a portion of an umbrella rib and stretcher embodying my invention, said stretcher being in partially open condition.

Figure 2 represents a longitudinal section thereof.

Figure 3 represents a side elevation thereof at a right angle to Figure 1.

Figure 4 represents a perspective view of a portion of the stretcher embodying my invention.

Figure 5 represents a longitudinal section of the bearing member for the pivot of the 40 joint of the rib and stretcher.

Figure 6 represents a transverse section on line 6—6 Figure 3.

Figure 7 represents a transverse section on line 7—7 Figure 3.

Figure 8 represents a side elevation similar to Figure 1 showing, however, the stretcher in folded condition.

Figure 9 represents an elevation of another embodiment of my invention.

50 Figure 10 represents a transverse section on line 10—10 Figure 9.

Figure 11 represents a longitudinal section thereof.

Figure 12 represents a perspective view

of a portion of a stretcher removed from 55 Figure 11.

Figure 13 represents a perspective view of the bearing member for the pivot of the joint of the rib and stretcher shown in Figures 9 and 11.

Figure 14 represents an elevation of another embodiment of the invention.

Figure 15 represents a perspective view of a stretcher showing another embodiment of the invention.

Similar numerals of reference indicate corresponding parts in the figures. Referring to the drawings,

1 designates the rib of an umbrella, and 2 designates a stretcher which is connected therewith in a manner hereinafter described, both stretcher and rib being of channelled or U shape.

3 In the channel of the rib at the place of junction of the stretcher with said rib there 75 is fitted the pin 3 which is firmly secured to the rib by swedging or pressing the material of the rib tightly against the side of the pin as at 4, said pin having therein at one end an opening to receive the axial pivot 5 which is passed through an opening in the ear 6 on the adjacent terminal of the stretcher, the ends of said pivot being headed on the exterior of said ear so that said ends are inclosed by the sides of the 80 channelled or U-shape rib and so removed from the exterior of the sides of the rib.

The crown of the stretcher near the pivotal end is swedged as at 7 whereby the relative walls of the channel of the stretcher are 85 reversed so that portions of the channel project in opposite directions. The portion at the end is reduced or flattened and entered into the adjacent portion of the channelled rib with which it is connected by the pivot 5 while the major portion of the stretcher is adapted to receive the corresponding portion of the rib and to embrace the latter. By this provision the stretcher and rib fold compactly together in the closed condition 90 of the umbrella, thus reducing their thickness as thus folded and preventing lateral disconnection of the same and relieving them of lateral torsion or twisting.

In Figures 1, 2, 3, and 5, the end of the pin 3 is shown with a single ear 8, in which is formed the opening 9 to receive the pivot 5, and the end of the stretcher is formed

with separated ears 6 to receive said pivot, said ears 6 being on opposite sides of said ear 8, the heads of said pivot being on the exterior of said ears 6, and so inclosed with 5 in and by the side of the channel of the rib, said pin in this case being solid, but to which I do not limit myself.

In Figures 9, 10 and 11 the pin is tubular and so has a plurality of ears 11, while the 10 stretcher has its ears 10 contacting and mounted within said ears 11 on the pivot 5 so that the ears 11 are on the exterior of the ears 10, said pivot having its heads on the exterior of the ears 11 and as in the previous 15 case inclosed within and by the side channel of the rib.

In Figure 14, the stretcher has at its pivotal end a plurality of ears 6. In Figure 15, I show a stretcher provided with inverted 20 channels one at each end thereof, one of the ends being pivotally connected with the rib and the other end being pivotally connected with a runner of the umbrella.

Having thus described my invention what

I claim as new and desire to secure by Letters Patent, is:—

1. A channelled stretcher in umbrella construction having a reversed channel at an end thereof.

2. In an umbrella construction, a channelled stretcher having at an end thereof a reversed channel and a channelled rib, the main channelled portion of the stretcher being of a size to receive said rib and embrace the walls thereof.

3. In an umbrella construction, a channelled stretcher having its channel at an end portion thereof projecting in reversed directions, and a channelled rib the pivotal end of said stretcher being mounted in said rib, and the main channel portion of the stretcher being of a size to receive said rib and embrace the walls thereof.

WAYNE S. EVANS.
